UNITED STATES PATENT OFFICE.

EDWARD DENIVELLE, OF MOUNT VERNON, AND JOSEPH COSGROVE, OF YONKERS, NEW YORK.

DESIGN FOR A STATUETTE.

SPECIFICATION forming part of Design No. 36,213, dated February 3, 1903.

Application filed October 15, 1902. Serial No. 127,426. Term of patent 3½ years.

To all whom it may concern:

Be it known that we, EDWARD DENIVELLE, a citizen of France, residing at Mount Vernon, and JOSEPH COSGROVE, a citizen of the United States, residing at Yonkers, in the county of Westchester and State of New York, have invented and produced a new, original, and ornamental Design for a Statuette, of which the following is a specification, reference being had to the accompanying drawings, forming part thereof.

Figure 1 is a front view, Fig. 2 a side view, and Fig. 3 is a rear view, of the statuette of a man wearing a long ulster coat which reaches to the ankles and which has a collar turned up around the neck. The hands are in the ulster-pockets at the breast, with the thumbs sticking out. On the head is an old-fashioned silk hat, while the letter A indicates a hand-kerchief protruding from the pocket of his coat. The head is turned slightly to the left.

We claim—

The ornamental design for a statuette, as herein shown and described.

EDWARD DENIVELLE.
JOSEPH COSGROVE.
